[57] CLAIM

The ornamental design for a spouted closure, as shown
and described.

DESCRIPTION

FIG. 1 is a top perspective view of a spouted closure
showing my new design;

FIG. 2 is a top plan view thereof;

FIG. 3 is an exploded side elevational view thereof, the
opposite side view being a mirror image thereto;FIG. 4 is an end elevational view thereof, the opposite
end view being identical thereto;

FIG. 5 is a bottom plan view thereof;

FIG. 6 is a bottom plan view of the spout closure,
shown separately for clarity of illustration; and,FIG. 7 is a cross-section view thereof, taken in the
direction of the arrows along line 7—7 of FIG. 1.FIG. 1

FIG. 2

FIG. 3

*FIG. 4**FIG. 5**FIG. 6*

FIG. 7
